UNITED STATES PATENT OFFICE.

WILLIAM H. DOANE AND GEORGE W. BUGBEE, OF CINCINNATI, OHIO.

BORING ATTACHMENT FOR MORTISING-MACHINES.

SPECIFICATION forming part of Letters Patent No. 295,236, dated March 18, 1881.

Application filed August 9, 1883. (No model.)

To all whom it may concern:

Be it known that we, WILLIAM H. DOANE and GEORGE W. BUGBEE, citizens of the United States, residing at Cincinnati, Ohio, have invented new and useful Improvements 5 in Boring Attachments for Mortising-Machines, of which the following is a specification.

This invention relates to boring-machines, 10 and is especially advantageous in mortising-machines used in car and other similar work, in combining in a compact and convenient manner an attachment for boring mortises with an auxiliary attachment for boring bolt-holes; and to this end it consists in a novel 15 construction and arrangement of mechanism for driving both the main and auxiliary boring attachments from the main counter-shaft and pulley under control of the operator, as 20 more fully hereinafter set forth.

Mechanism embodying our invention is illustrated in the accompanying drawings, in which Figure 1 is a rear elevation of the mortising or boring machine, omitting in this and 25 the following figures all parts excepting those concerned in driving the boring-tools. Fig. 2 is a side elevation of the same, and Fig. 3 is a horizontal section taken through the frame of the machine, and through the counter-shaft and 30 bearings of the main boring attachment.

The parts hereinafter referred to are indicated in the drawings by letters of reference.

In the figures of the drawings, A designates the frame of the machine; B, the principal counter-shaft, from which the mortiser and boring attachments are driven; and C C', the counter-shafts of the main and auxiliary boring attachments, respectively. The two latter shafts are journaled in parallel bearings 35 at the sides of the supporting-column A, the boring-bits *a b* being arranged vertically in suitable housings and rotated by intermeshing bevel-gears in the usual manner. The counter-shaft B is provided with the ordinary fast and loose pulleys, *c d*, by which the machine receives its power from the line-shafting of the establishment or other source, and transmits its power by a pulley, *e*, of sufficient 40 width to permit its belt to be shifted from one to another of two adjacent pulleys, *f g*, upon the counter-shaft C, which thus receives its

power. The pulley *f* is secured to the counter-shaft C at its end, and drives the main boring-bit *a* directly. The pulley *g*, however, is secured upon a loosely-rotating sleeve, *h*, 55 embracing the shaft C and extending inward through the bearing *i*. The sleeve extends far enough to carry a pulley, *j*, by which it transmits its power to the auxiliary counter-shaft C' and bit *b*. The pulley *j* is of double 60 width, and is arranged opposite fast and loose pulleys *m n* upon the counter-shaft C', the belt passing through the frame or supporting column A, which has a suitable aperture for the purpose, and a proper shifting device being 65 provided under control of the operator.

In operation, the belt *g'* is normally in the position shown in Fig. 2, engaging the pulley *g* and the sleeve *h*. The belt *k* then engaging the loose pulley *m* of the counter-shaft C' both 70 boring-bits are at rest. Either one of the bits may be thrown into operation, as may be desired, by shifting the proper belt to the adjacent pulley. Thus the belt *g'* being shifted from its indicated position to engagement with 75 the pulley *f*, the boring-bit *a* will be operated; but the belt *g* being restored to its indicated position, and the belt *k* shifted to engage the fast pulley *n* of the counter-shaft C', the bit *b* 80 will be brought into operation.

We claim as our invention and desire to secure by Letters Patent—

1. In a mortising and boring machine, the main and auxiliary boring attachment arranged relatively to each other, substantially 85 as described, driving mechanism leading from the main counter-shaft to one of the boring-shafts, and driving mechanism, substantially as described, leading therefrom to the other boring-shaft, and mechanism for throwing the 90 latter into or out of operation, all in combination, substantially as set forth.

2. In a mortising and boring machine, main and auxiliary boring attachments at opposite sides of the supporting-column, a belt connecting the same, means for throwing said belt into or out of operation, a counter-shaft on the main frame, and a belt connecting this with one of the boring-shafts, all combined and arranged to operate as set forth. 95

3. In combination, in a mortising-machine having boring attachments, a counter-shaft 100

journaled on the main frame and connected to the main boring-spindle, a fixed pulley on said counter-shaft, an adjacent pulley secured to a loose sleeve, the auxiliary boring-tool and its 5 counter-shaft driven from said pulley on the sleeve, and the driving-belts, all combined substantially as stated.

4. In a mortising-machine, the combination of the boring counter-shaft C, having thereon 10 a fixed pulley, f, and a loose sleeve, h, carrying pulleys g and j, with a second boring

counter-shaft, C', provided with fast and loose pulleys m n, substantially as and for the purpose specified.

In testimony whereof we have hereunto set our hands and seals in the presence of two subscribing witnesses.

WILLIAM H. DOANE. [L. S.]
GEORGE W. BUGBEE. [L. S.]
